PUMP FOR THE TREATMENT OF WATER WITH CHEMICALS OR THE LIKE

Nat Cordis, Crown Farm, Silver Lake, Wis.

Filed June 12, 1961, Ser. No. 65,545

Term of patent 14 years

(Cl. D65—1)

Fig. 1.

FIGURE 1 is a perspective view of a pump for the treatment of water with chemicals or the like, embodying my new design;

FIGURE 2 is a perspective view taken from the end opposite that shown in FIG. 1 on an enlarged scale; and

FIGURE 3 is a perspective view taken from the side opposite that shown in FIG. 2.

I claim:

The ornamental design for a pump for the treatment of water with chemicals or the like, as shown.
